UNITED STATES PATENT OFFICE.

BENJAMIN HETHERINGTON, OF FALL RIVER, MASSACHUSETTS.

HARNESS HOOK FOR LOOMS.

Application filed November 25, 1927. Serial No. 235,608.

My invention relates to a harness hook which is adapted to support a series of harnesses within the loom. I have found that by the use of a specially constructed hook 5 that it is possible to support a series of harnesses from one strap. In present practice it is usual to employ a separate hook for each harness and in said cases as many as two harnesses are supported from one 10 hook, but this is not satisfactory inasmuch as the hooks leading to the harnesses have a tendency to crawl up the sides of the arcuate base of the hook which is secured to the harness strap. This tendency is a 15 serious drawback in that it causes crowding of the harnesses with the result that the yarn wears out and the ends are easily broken. In the weaving of cloth a better 20 result is generally obtained if the harnesses in the series which alternate in their reciprocatory movement are each disposed a little distance above the other in a graded relation as a greater clearance is given and less tension placed on the yarn. I have found 25 that by the use of a hook having a substantially triangular contour with hooks of progressively varying lengths disposed on the horizontal bar that the graded relation of the harnesses is obtained without any crowding 30 of the harnesses together.

It is an object of my invention to produce a harness hook for use in looms which is simple in structure and reliable in operation.

Another object of my invention is to provide a harness hook of a substantially triangular contour having hooks thereon which are secured to the harnesses and are adapted 35 to maintain the harnesses in a graded relation without any tendency to crowd together.

Still another object of my invention is to provide a harness hook which is capable of supporting several harness members whereby the straps, rollers, hooks and jacks that are necessary to support the harness members are greatly reduced in number thereby causing a great saving. This is made possible by reason of the fact that one hook 45 does the work of two or more.

Other objects and advantages will appear from the following detailed description taken in connection with the accompanying drawings.

I attain these objects and advantages by 55 means of the mechanism illustrated in the drawings wherein:

Figure 1 is a front elevational view of the upper portion of a loom showing the loom arch together with the harness straps 60 and the improved harness hooks with sufficient of the harnesses being shown to illustrate the mode of attachment.

Figure 2 is an elevational view of the lower part of the harnesses showing the 65 mode of attachment of the hooks to the harnesses and from the harnesses to the treadle means through the jacks and straps.

Figures 3 and 4 are front and side elevational views of the complementary harness 70 hooks, the upper series of hooks being used to secure the upper part of the harnesses whereas the lower series is secured to the lower part of the harnesses. It is to be noted that the upper hook is provided with an enlarged opening for the reception of the strap whereas the lower hook is provided with a screw end for its insertion into the jack.

Similar numerals refer to similar parts throughout the several views. 80

Referring to the drawings, 1 is a loom arch having the bearings 2 on which the shaft 3 is supported. Mounted on the shaft 3 are the rollers 4 having straps 5 secured thereto by the screws 6. The other ends of the 85 straps are provided with a clip 7 which is adapted to fit within notches 8 provided on the strap for the purpose of adjustment. Harness hooks are attached to the ends of the straps for supporting the harnesses 9 and 10. 90 As shown in the drawings the harnesses are in series of three.

The hooks, by means of which these harnesses are attached to the straps, form the distinctive feature of this invention, and, as 95 may be seen from Figures 3 and 4 of the drawings, the upper hook comprises essentially a shank 10 having the triangular loops 11 and 12 disposed at right angles to each other and integral with said shank. This, of course, may be manufactured by twisting the wire into the necessary form and as the method for doing such is familiar to any one skilled in the art, no discussion will be here made as to the mode of manufacture.

The upper loop is adapted to receive the strap 5 by which the same is suspended from the shaft 3. Mounted on the loy 105 12

are the hooks 13, 14, 15 which, as may be seen from the drawings, are graded in length. The lower hook which is attached to the lower part of the harnesses, as shown in Figure 2, comprises a triangular loop 16 having a screw stem 17 which may be inserted into the jacks 21. Hooks 18, 19, 20 of the same size as 13, 14, 15, but reversed as to position thereto so that the longest hook 10 in one series opposes the shortest hook in the other series as shown clearly in Figure 4. The turned up portions of the hook which catch in the hook eyes 9 on the harness frames are at right angles to the horizontal portion of the lower loop 12. In Figure 2 the mode of attachment of the lower hook is shown clearly, the hooks being secured to hook eyes on the lower bar of the harness frames and are secured to the jacks 21. The jacks in turn are strapped to the treadles 22 by means of the straps 23.

Reverting to the particular structure of the harness hook it should be noted that the horizontal portion of the loops 12 and 16 to which the hooks 13, 14, 15 and 18, 19, 20 are secured is of such construction as to allow the hooks complete freedom of movement in a horizontal direction without any tendency to crawl up the sides or to become bunched together. This differs greatly from the hooks now in use which have a circular loop for holding the individual harness hooks which by reason of the arcuate base, in cases where two or more hooks are used, causes the hooks to climb up the sides whereupon the harnesses bang together. Because of this limitation in the hook now in general use no more than two individual hooks are mounted on the same hook attached to the strap and where it is necessary to hook up three harnesses to work at the same time extra straps, rollers and jacks are necessary. It will be appreciated that with the applicant's proposed hook in the ordinary loom having six harnesses and assuming that two harnesses are attached to one hook that the substitution of applicant's hook will eliminate the need for four rollers, six straps, two jacks and four hooks which is an immense saving as to materials. In other words, in the construction now to be found it is customary to join two harnesses to one hook and the third harness to another hook so that four sets of hooks are necessary for securing the two series of harnesses to the straps.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure which utilize the principle of my invention and fall within the

purview of my invention and are within the spirit and scope of the following claims:—

The invention having been set forth, what is claimed as new and useful is:

1. In combination with a loom having a series of harnesses, harness straps, jacks, a harness hook comprising in combination a wire member, said wire member having a shank portion, said wire member having a loop formed at one end thereof, means at the other end of said shank for attachment to either a harness strap or a jack, said loop having a horizontal portion, a plurality of individual hooks on said horizontal portion for holding said harnesses, said horizontal portion being of sufficient length to provide clearance for said individual hooks.

2. In a loom having harness members, harness straps, treadles, jacks, complementary hook members for supporting said harness members comprising a top hook member attached at one end to one of said harness straps, said top hook member having a substantially triangular loop at its other end, a plurality of individual hook members for each of said harness members disposed on the horizontal portion of said loop, said harness members being secured at their bottom portions by a bottom hook member, said bottom hook member comprising means at one end for securing same to one of said jacks, a substantially triangular loop at the other end having a plurality of individual hooks corresponding to said first mentioned disposed individual hooks and coacting therewith on its horizontal portion, said top and bottom hook members being adapted to secure a plurality of said harnesses from one leather strap and one jack, the harness members being restrained against banging together.

3. In combination with a loom having a series of harnesses, harness straps, jacks, a harness hook comprising in combination a wire member, said wire member having a shank portion, said wire member having a loop formed at one end thereof, means at the other end of said shank for attachment to either a harness strap or a jack, said loop having a horizontal portion, a plurality of individual hooks on said horizontal portion for holding said harnesses, said horizontal portion being of sufficient length to provide clearance for said individual hooks, said individual hooks being of progressively varying lengths to hold said harnesses in a graded relation.

4. In a loom having harness members, harness straps, treadles, jacks, complementary hook members for supporting said harness members comprising a top hook member attached at one end to one of said harness straps, said top hook member having a substantially triangular loop at its other end,

a plurality of individual hook members for each of said harness members disposed on the horizontal portion of said loop, said harness members being secured at their bottom 5 portions by a bottom hook member, said bottom hook member comprising means at one end for securing same to one of said jacks, a substantially triangular loop at the other end having a plurality of individual hooks cor- 10 responding to said first mentioned disposed individual hooks and coacting therewith on its horizontal portion, said top and bottom hook members being adapted to secure a plu-

rality of said harnesses from one leather strap and one jack, the harness members being restrained against banging together, said individual hooks on the top and bottom hook members being of progressively varying length, the longest hook in the top series 15 opposing the shortest hook in the lower series 20 and conversely, whereby the harness members are held in a graded relation to give more clearance during the operation of the same.

In testimony whereof I have affixed my signature.

BENJAMIN HETHERINGTON.
